UNITED STATES PATENT OFFICE

146,491

DESIGN FOR A COMBINATION CLOCK AND
DESK UNIT

Joseph J. Swartzmiller, Carnegie, Pa.

Application June 24, 1946, Serial No. 130,988

Term of patent 3½ years

(CL. D42—7)

To all whom it may concern:

Be it known that I, Joseph J. Swartzmiller, a citizen of the United States and a resident of Carnegie, in the county of Allegheny and State of Pennsylvania, have invented a new, original, and ornamental Design for a Combination Clock and Desk Unit, of which the following is a specification, reference being had to the accompanying drawings, forming part thereof, wherein

Figure 1 is a rear-and-end perspective view showing of the combination clock desk unit embodying my new design.

Figure 2 is a front-and-end perspective view of the unit as viewed from the same end thereof as in Figure 1.

Figure 3 is a front-and-end perspective view showing of the unit as viewed from the opposite end thereof as in Figure 3.

Figure 4 is a transverse sectional view taken in an upright plane through the line 4—4 in Figure 2.

I claim:

The ornamental design for a combination clock and desk unit, substantially as shown.

JOSEPH J. SWARTZMILLER.
